[57] CLAIM

The ornamental design for a holder for an open book, as shown and described.

DESCRIPTION

FIG. 1 is a front elevational view of a holder for an open book, showing my new design;

FIG. 2 is a right side elevational view thereof, the left side view being a mirror image;

FIG. 3 is a top plan view thereof;

FIG. 4 is a rear elevational view thereof;

FIG. 5 is a bottom plan view thereof;

FIG. 6 is a front elevational view of a second modified embodiment thereof;

FIG. 7 is a right side elevational view of FIG. 6, the left side view being a mirror image;

FIG. 8 is a top plan view of FIG. 6;

FIG. 9 is a rear elevational view of FIG. 6;

FIG. 10 is a bottom plan view of FIG. 6;

FIG. 11 is a front elevational view of a third modified embodiment thereof;

FIG. 12 is a right side elevational view of FIG. 11, the left side being a mirror image;

FIG. 13 is a top plan view of FIG. 11;

FIG. 14 is a rear elevational view of FIG. 11; and

FIG. 15 is a bottom plan view of FIG. 11.
